UNITED STATES PATENT OFFICE

WALTER D. MORRISON, OF DETROIT, MICHIGAN

FORMING DEVICE

Application filed November 22, 1929. Serial No. 409,135.

This invention relates to certain novel improvements in forming devices and more particularly to a forming device used in connection with the forming of glass tubing and the like into predetermined shapes and has for its principal object the provision of an improved construction of this character which will be highly efficient in use and economical in manufacture.

The salient object of my invention is to provide a forming device which may be used in connection with the forming of glass tubing or the like into predetermined shapes and which will embody an arrangement whereby portions of the tubing may be bent over other portions of the tubing.

Another object of the invention is to provide a device of the above described character which will be of simple construction so that the number of parts thereof will be reduced to a minimum which will facilitate and simplify the use of the device.

A still further object of the invention is to provide a device of the above described character which may be used in connection with glass tubing or the like that is in a very heated condition.

Other objects will appear hereinafter.

The invention consists in the novel combination and arrangement of parts to be hereinafter described and claimed.

The invention will be best understood by reference to the accompanying drawing, showing the preferred form of construction and in which:

Fig. 1 is an elevational view depicting a preferred form of construction for my invention;

Fig. 2 is a fragmental elevational view of the device illustrated in Fig. 1 looking in the opposite direction with the tool in an inverted position;

Fig. 3 is a fragmental view similar to Fig. 1 depicting a movable portion of my invention in inoperative position;

Fig. 4 is a sectional view taken substantially on the line 4—4 on Fig. 1; and

Fig. 5 is a sectional view taken substantially on the line 5—5 on Fig. 1.

In the accompanying drawing wherein I

have illustrated the preferred form of construction for my invention, 10 indicates a flat plate which forms the main body portion of my improved device. The embodiment of the invention illustrated is that of a forming tool particularly adapted for the formation of the letter "R". Extending upwardly from one face of the plate 10 parallel to the edge 11 and away from the edge 12 I provide an upstanding rib 13. Extending transversely of the plate 10 in spaced relation with the edge 14 thereof a continuation 15 of the rib 13 is provided and this continuation extends substantially at right-angles to the rib 13. The portion 15 terminates in a semi-circular portion 16 which is disposed with the curvature thereof directed away from the rib 13. The rib arrangement thus far described might be used in the formation of the letter "P". By referring to the drawing it may be seen that the device in the present instance does not have a rib extending from the outer end of the semi-circular portion 16 parallel to the portion 15. Extending at an angle with the rib 13 toward the edge 17 of the plate 10 is an upstanding rib 18, the inner end of which is spaced from the free end of the rib portion 16.

My invention is intended to be employed in connection with the formation of letters from glass tubing, which letters are employed in the making of gas filled tubing electric signs. If desired the device may be used in connection with the tube making machine as the glass tubing as it is delivered from such a machine is in a heated and pliable condition. In the formation of the letter "R" the glass would be arranged in abutment with the rib portion 13 with one end thereof adjacent the edge 12. The tubing is then directed up along the rib 13 and along the rib 15 and around the semicircular portion 16 back toward the rib 13. It is customary at this point to bend the tube to extend for a short distance back along the portion extended toward the rib 13 and the tube is then bent into engagement with the rib 15. A tube bent in this manner is depicted in dotted lines in the drawing and is indicated by 19. An important feature of my invention resides in an arrangement

which will facilitate the bending of a tube back along the portion disposed to extend toward the rib 13 from the end of the rib 16.

The arrangement for facilitating this just set forth bend includes the opening 20 formed in the block 10. Extended through this opening 20 is a member 21, the lower end of which is fixed to a lever 22 that is pivotally mounted as indicated at 23 on the lower side of the plate 10. At the upper end of the member 21 a forwardly extending portion 24 is provided on which a block 25 is mounted, the block 25 being spaced from the upper surface of the plate 10 in an amount sufficient to permit a section of the tubing 19 to be disposed intermediate the lower surface of this block 25 and the upper surface of the plate 10. A spring 26 extends between the lever 22 and a stud 27 is fixed on the under surface of the plate 10 and this spring serves to normally hold the member 21 and the block 25 in the position depicted in Fig. 3. A handle 28 is connected to the lever 22 and is disposed in the position best illustrated in Fig. 1.

In use, a section of glass tubing in heated condition, preferably from a tube making machine or a tube made by hand from molten glass while still in a plastic condition, is directed around the ribs in the manner set forth and after a section thereof has been directed around the portion 16 a portion is directed toward rib 13 and if desired a portion may be cut from the rib 13 to facilitate this directing of the tubing 19. After the tubing 19 has been directed in this manner the handle 28 is manipulated to move the member 21 and the block 25 from the position depicted in Fig. 3 into the position depicted in Fig. 1, and it is therefore manifest that the section of tubing may be bent back over the upper surface of the block 25 and then down along the rib 18.

It is manifest that the particular disposition of the member 21 and the block 25 will vary dependent upon the letter being formed for the bending of a section of tubing over another section in the manner set forth or as it is called doubling back is required in the formation of the majority of letters and it is within the purview of this invention to locate the portion about which the portion is bent back at the position required.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

Having thus described my invention what I claim as new and desire to protect by Letters Patent is:

1. In a device of the character stated, a member and stationary guiding means thereon, movable guiding means, means for moving said movable guiding means, and means for normally holding said movable guiding means from guiding position.

2. A device for forming characters from glass tubing in plastic condition comprising a relatively stationary base, upstanding guiding means on said base of a predetermined configuration and around which said tubing is adapted to be directed, a member movable over and relative to said base and providing a pivot for holding one portion of said tubing so that said tubing may be bent with said member as a pivot and means including a handle for moving said member over, and relative to said base.

3. A device for forming characters from glass tubing in plastic condition comprising a base having an opening extending therethrough, upstanding guiding means on one surface of said base of a predetermined configuration and around which said tubing is directed, and a member movable through said opening and having a head disposed thereabove providing a pivot for holding one portion of said tubing so that said tubing may be doubled back upon itself, and means for moving said member in said opening, said means including a handle pivotally mounted on said base on the surface thereof opposite said first named surface, said handle including a portion connected to said member, and resilient means for normally urging said head toward one end of said opening.

4. A device for forming configurations in material in plastic condition, comprising a relatively stationary base, material guiding means projecting from said base, of a predetermined configuration and around which said material is adapted to be directed, a member movable over and relative to said base and providing a pivot for holding one portion of said material so that said material may be bent with said member as a pivot, and means including a handle for moving said member over, and relative to, said base.

In testimony whereof I affix my signature.

WALTER D. MORRISON.
